 tion of New York

Application April 4, 1941, Serial No. 386,921

6 Claims. (Cl. 66—106)

This invention relates to knitting machines, and more especially to knitting machines of the cylinder and dial type, wherein the knitted loops are produced by a circular ring of needles and associated web holders.

Heretofore, in machines of this type, the needles have been mounted on a needle cylinder so that they are movable in an upward and downward direction, and the web holders have been mounted in a separate ring attached to the outside of the needle cylinder in radially spaced relation thereto, with the web holders movable bodily towards and away from the cylinder in a radial direction. Considerable difficulty has been experienced with such a construction because of the tendency of dirt and lint to collect in the space between the needle cylinder and the web holder ring, interfering with the operation of the needles and web holders, and requiring frequent dismounting of the parts to permit their being cleaned.

In addition, it has been found that tension on the knitted loops and the fabric cannot be maintained uniform to keep the loops or stitches even, as is desired in any good quality fabric. The web holders were incapable of compensating for variations in the length of the stitch loops, so that if the web holders were set for a long loop and the needles should happen to draw short loops, the web holders would cut or break the thread.

With the foregoing experiences and defects in mind, it has been my aim to provide a materially improved knitting machine which is simple in construction of its component parts, easy to assemble and disassemble, and simple to adjust. The machine which constitutes the invention of this application is especially smooth in its operation and in many respects is far superior to any other machine of its general type of which I am aware.

Another principal object of this invention is to provide an improved needle and web holders assembly wherein both the needles and web holders are mounted on a common cylinder, which is preferably constructed of two parts for convenience of manufacture and assembly.

Another object of the invention is to provide a simple form of yieldable holding means common to the needles and web holders for preventing their inadvertent displacement from the cylinder, while also permitting quick and easy removal or replacement of either the needles or web holders, without disturbing the other, and without dropping stitches on those needles which are not to be removed or replaced.

A still further important object of the invention is to provide a rotatable cam ring for carrying a plurality of cams which serve to actuate the needles and web holders respectively, to-

gether with novel adjusting instrumentalities for quickly and easily adjusting said cams.

The invention also contemplates an improved and novel form of pivotal or rocking web holder, and a simple and effective mounting and actuating means therefor, whereby the web holder will automatically adjust itself to fit the stitch loop drawn by an associated needle and will keep the knitted fabric snug and under the desired tension required for uniformity of knitting action.

Other and further objects of the invention will be hereinafter described, and the novel features thereof defined in the appended claims.

15. In the drawings:

Figure 1 is a fragmentary vertical sectional view, taken centrally through a knitting machine constructed in accordance with the present invention;

20. Figure 2 is an enlarged fragmentary vertical sectional view, taken at a position about the needle circle at which the web holders are rocked inwardly, one of the web holders and one of the adjacent needles, and certain of the cam regulating instrumentalities, being shown in elevation;

25. Figure 3 is a sectional view generally similar to Figure 2, taken at another position about the needle circle, and showing the web holder rocked outwardly;

30. Figure 4 is an enlarged fragmentary vertical sectional view, taken on the line 4—4 of Figure 1, looking in the direction of the arrows;

35. Figures 5 and 6 are horizontal sectional views taken respectively on the lines 5—5 and 6—6 of Figure 1, with the needles and cylinder omitted, and particularly showing the web holder operating cams which rock the web holders inwardly and outwardly, respectively;

40. Figure 7 is a view in vertical section through the needle cylinder, with the needles omitted, and showing one of the web holders in elevation, and also showing in elevation one of the cylinder insert plates which serves to guide an associated needle in the upward and downward movement of the latter;

45. Figure 8 is a fragmentary horizontal sectional view, taken on the line 8—8 of Figure 4, and particularly showing the adjustable mounting for one of the needle draw-cams;

50. Figure 9 is a fragmentary somewhat diagrammatic view in elevation, with the cam ring removed, but showing certain of the needle draw-cams, raise-cams, and web holder cams in their relative cooperative positions, the needle and web holders being also shown in their relative positions corresponding to the cooperative functions produced by the respective cams;

55. Figure 10 is a fragmentary horizontal sectional view, taken on the line 10—10 of Figure 9;

Figures 11, 12, 13 and 14 are corresponding fragmentary elevational views, respectively, of the upper section of the needle cylinder, the lower section of the needle cylinder, the retaining ring for the inserted needle guide plates, and the bed plate;

Figure 15 is a fragmentary top plan view of the cylinder with the web holders assembled thereon and the needles omitted, certain of the web holders being shown in their inwardly rocked position, and certain other web holders in their outwardly rocked positions;

Figure 16 is an enlarged view in side elevation of one of the needles, the needle hook and latch being shown on a somewhat exaggerated scale;

Figure 17 is a view in side elevation of a modified form of web holder and an associated needle, as used for knitting loop-surfaced fabrics; and

Figure 18 is a fragmentary view in end elevation of a web holder corresponding to the construction in Figure 17, and showing diagrammatically the relative positions of the double thread feed employed with this type of web holder to produce loop-surfaced fabrics.

Like reference characters designate corresponding parts in the several figures of the drawings, wherein 1 denotes the bed plate of the machine, which is supported by a suitable type of housing 2 above a base plate 3 having legs 4 for elevating the working parts of the machine at any desired height above the floor. Fixed to the bed plate 1, as by screws 5, is an axially upright needle cylinder, generally designated 6, this needle cylinder being stationary and rigidly supported by the bed plate 1. Mounted on the needle cylinder is a circle of needles which are arranged in circumferentially spaced relation to each other about the cylinder, with the longitudinal axes of the needles disposed vertically, the needles being generally designated 7. Also mounted on the needle cylinder 6 and disposed intermediate the needles is a plurality of web holders, generally designated 8, there being one web holder between each adjacent pair of needles. The size of the needle cylinder, and the number of needles and web holders, may be varied according to the size of the fabric to be knitted, which fabric is knitted in tubular form and extends downwardly through the needle cylinder, as generally indicated at 9, to a suitable take-up mechanism (not shown), for taking up the fabric as it is progressively knitted during the operation of the machine.

Encircling the needle cylinder in radially spaced relation thereto is a cam ring, generally designated 10, said cam ring carrying a plurality of cams, generally designated 11, 12, 13 and 14. The cams 11 and 12 cooperate with the web holders 8 to impart radial inward and outward rocking or pivotal movement to the web holders, as will hereinafter more fully appear. Cam 13 will be hereinafter referred to as the needle draw-cam, and cam 14 will be hereinafter referred to as the needle raise-cam, these cams serving to impart downward and upward movement, respectively, to the needles 7 in timed relation to the rocking or pivotal movements imparted to the web holders by the web holder-cams 11 and 12.

The cam ring 10 is fixed to the upper side of a ring gear 15, preferably by means of screws 16 extending downwardly through the cam ring and into the ring gear. As clearly shown in Figures 1 to 3, inclusive, the bed plate 1 is provided with an annular recess 17 in which the teeth 18 of the ring gear 15 are disposed, and the bottom of the bed plate is suitably slotted at any desired point

to permit a drive gear (not shown) to mesh with the teeth 18 on the ring gear 15 and impart rotation to the ring gear and cam ring 10.

For convenience of manufacture and assembly, the cam ring 10 is preferably composed of several segments, each of which is independently secured to the ring gear 15 by a pair of the bolts 16 located respectively near the opposite ends of the segment. By reason of this construction, convenient access may be had to any part of the needle circle and corresponding section of web holders on the cylinder 6 by removing only a single segment of the cam ring 10, thus eliminating the necessity of dismounting the entire cam ring.

Likewise, for convenience of manufacture and assembly, the needle cylinder 6 is preferably composed of two parts comprising an upper cylindrical section 6' and a lower cylindrical section 6''. The upper section 6' is preferably provided at its lower end with an annular flange 19 which is adapted to overlap upon a corresponding annular flange 20 on the upper end of the lower section 6'', and the two sections are rigidly joined together at the overlapping joint by screws 21 extending through the flanges above referred to.

The upper section 6' of the needle cylinder 6 is slotted at its outer face, as indicated at 22, the slots being axially extended from the upper end of the cylinder to the lower end of the upper section, and being circumferentially spaced equidistantly from each other, as clearly indicated in the drawings. An annular groove 23 extends about the cylinder section 6', intersecting the slots 22 near the lower ends thereof. Additional slots 24 are formed radially in the upper edge of the cylinder section 6', registering with the respective slots 22 on the face of the cylinder. A web holder 8 is disposed in each of the slots just referred to, the body of each web holder lying in one of the slots 22 with the arm 8' at the upper end of each web holder lying in one of the radial slots 24. As best shown in Figures 1 to 3 and 7, the body of each web holder is provided near its lower end with an inwardly projecting lug or boss 25, lying in the plane of the body of the web holder so that when the web holder is disposed in a groove 22, the lug or boss 25 will be disposed in the annular groove 23 and serve as a fulcrum or pivot for the web holder, about which the web holder is free to rock towards and away from the central axis of the needle cylinder.

Formed in the outer face of the lower section 6'' of the needle cylinder 6 is a second set of slots 26, which are axially extended from top to bottom thereof. The pitch of the slots 26 is preferably equal to the pitch of the slots 22, but the slots 26 are preferably slightly greater in width than the slots 22. Disposed in each of the slots 26 is an insert 27 which serves to guide the needles 7 in their upward and downward movement, it being understood that one needle is disposed between each adjacent pair of inserts 27, as will be best seen from Figure 7. The upper end of each insert is engaged in a notch 28 formed in the upper section 6' of the needle cylinder 6, and the lower end of each insert is radially extended inwardly at 29 and formed with a notch 30 to receive a correspondingly shaped protuberant annular rim 31 formed on the bottom of the lower cylinder section 6''. A retaining ring 32 is clamped against the lower end of the needle cylinder by means of the bolts 5 hereinbefore referred to, the retainer ring having a laterally outwardly projecting flange 33

lying beneath the inserts 27 to positively maintain the inserts in firm interlocked assembly with the needle cylinder.

In order to impart upward and downward movement to the needles, two sets of needle cams are preferably employed, one set for raising the needles, and one set for lowering the needles. The raise-cams have been designated 14, the number of these cams corresponding to the number of thread feeds, and the cams being fixedly attached to the inside of the ring gear and cam ring 10 in any suitable manner, as by means of the screws 34. A corresponding draw-cam 13 is disposed at the inside of the ring gear and cam ring 10, as best shown in Figures 4 and 9, the number of draw-cams likewise corresponding to the number of thread feeds. The draw-cams 13 are preferably adjustably mounted so as to permit adjustment in an upward and downward direction for the purpose of enabling stitch loops of different lengths to be drawn by the needles during the knitting operation. To this end, each draw-cam 13 is attached, as by screws 35, to a cylindrical stem 36 which is flattened at one side for firm abutting engagement with the outer face of the cam member, as best seen in Figures 4 and 8. The stem 36 for each cam member is disposed in a guideway or bore 37 of corresponding shape, in which the stem is freely movable in an upward and downward direction. The lower end of the stem is provided with a cup-shaped recess 38, in which a coil spring 39 is seated. A retainer plate 40 is mounted below each bore or guideway for the stems 36, and serves as a seat for the lower end of the spring 39. Extending downwardly through the cam ring 10 from the upper side thereof and coaxially with the guide stem 36 on each draw-cam 13 is an adjusting screw 41, having its lower extremity in abutting engagement with the upper end of the stem 36. By screwing the adjusting screw 41 downwardly, the guide stem 36 and its corresponding draw-cam 13 will be urged downwardly against the yielding pressure of the spring 39. By screwing the adjusting screw upwardly, the pressure of the spring 39 will cause the guide stem 36 and its corresponding draw-cam 13 which is attached thereto, to move upwardly. Thus, the draw-cam will remain in any adjusted position in which it is set by the upward or downward screwing motion of the adjusting screw.

To illustrate the knitting action of the needles 7, it will be assumed that the cam ring 10 and the needle cams 13 and 14 are moving in a counter-clockwise direction about the central axis of the needle cylinder, as viewed from above the needle cylinder. This direction of rotation of the cam ring is indicated by the feathered arrow at the bottom of Figure 9. Accordingly, the inclined face 14' of the raise-cam becomes the cam face which engages the outwardly offset butts 7' of the needles and causes the needles to be successively raised upwardly as the cam face advances around the needle circle. Similarly, the inclined face 13' of the draw-cam 13 constitutes the cam face which engages the butts 7' of the needles to cause the needles to be successively drawn downwardly as the cam advances around the needle circle. It will be observed from Figure 9 that the cam face 13' of the draw-cam 13 is so arranged that it is sufficiently spaced above the raise-cam 14, and to one side of the cam face 14' of the latter, that the butts 7' of the needles do not engage the

cam face of the draw-cam until the needles have passed the peak of the raise-cam and have assumed the highest point of their upward movement, the space between the raise-cam and the draw-cam affording sufficient clearance to permit the needle butts 7' to pass between the cams during the downward movement imparted thereto by the draw-cam and the upward movement imparted thereto by a succeeding raise-cam.

It will be further observed that the peak of the raise-cam is disposed in substantial vertical alignment with the thread feed, indicated generally by the thread guides 42, the number of thread guides corresponding to the number of thread feeds which are preferably multiplied to present a thread to the needles of the needle circle at as many equally spaced points about the needle circle as may be conveniently accommodated by a machine of any selected size, thus increasing the rapidity of the knitting action. For the sake of simplicity of illustration, only one thread feed has been shown in the drawings, but it will be understood, as indicated above, that the feeds may be duplicated at as many points about the needle circle as may be desired. As an example, for a machine constructed according to the present invention and having a needle cylinder diameter of approximately eleven or twelve inches, as many as twenty-eight or thirty thread feeds may be provided about the needle circle, and a corresponding number of raise-cams and draw-cams, having the relative positions indicated diagrammatically in Figure 9.

The thread guides 42 are suitably mounted for rotation about the axis of the needle cylinder in the same direction and at a speed corresponding to the speed of rotation of the cam ring 10. Each thread, generally designated T, is fed from its source of supply (not shown) to the needles successively as the needles reach the upper limit of their movement in timed relation to the movement of the thread guides 42 about the needle circle, the thread being suitably guided through eyes 43 in the guide and being laid under the hooks 7" at the upper extremities of the needles. The needle latches 7''' will be open when the thread is presented to the needles at the upper limit of their movement, as will be obvious to those familiar with the art of knitting machines. As the needles successively move downwardly under the influence of the draw-cams 13, the thread is pulled downwardly by the needle hooks 7", drawing the thread across the arms 8' at the upper ends of the web holders 8 associated with each needle. As the downward movement of each needle continues below the upper end of its associated web holder, a new stitch loop is drawn through the stitch previously knitted and lying on the shank of the needle at the time that the needle draws the new stitch, the old stitch being ultimately cast off the needle, as permitted by the closing of the needle latch 7''' during the downward movement of the needle. Since this knitting action is conventional, further description thereof is unnecessary, and the function of the web holders will now be more particularly described in its relationship to the knitting action.

Disposed on the upper end of each web holder is a projection or nose 44, disposed in the plane of the arm 8' and spaced somewhat above the latter so as to overlie the base of the arm and provide a recess 45. The primary purpose of this

construction is to cause the web holder to normally engage the edge of the knitted fabric in the recess 45 as it is knitted, and to hold the fabric down snugly on the upper end of the needle cylinder, particularly during the upward or raising movement of the needles. According to the preferred construction and operation of the present invention, the web holders occupy the position shown in Figure 2 and in full lines in Figure 7, until the hook of the associated needle is drawn downwardly to a point just above the upper end of the web holder, whereupon the web holder is automatically rocked outwardly to the position shown in Figure 3 and in broken lines in Figure 7. This outward rocking movement of the web holder is produced by engagement of the cam 12 with the butt of the web holder which lies below the boss 25 on which the web holder is fulcrumed. The web holder remains in its outwardly rocked position referred to until the needle reaches approximately the lower limit of its downward movement, whereupon the web holder is rocked inwardly again by the cam 11 to restore the same to its fabric hold-down position during the succeeding cycle commencing with the raising of the needle. The extent of pivotal or rocking movement of the web holders successively about the needle circle is best illustrated in Figures 5, 6 and 15, being principally great enough to periodically disengage the nose 44 of the web holders from the knitted fabric and reengage the same in proper timed relation to the movement of the needles, the critical point of disengagement of the nose 44 occurring as the hook of the needle approaches the upper end of the web holder during the downward movement of the needle, and the critical point of reengagement occurring at the commencement of the raising movement of the needles to prevent the new loops from riding up with the needles and interfering with the formation of a succeeding stitch loop. It will be observed that when the web holders are rocked outwardly to the position disengaging the nose of the web holder 44 from the fabric, as best illustrated in Figure 3 of the drawings, the arm 8' of the web holder is not completely withdrawn from the radial slot 24, but is long enough to insure the drawing of the new stitch loop across the arm of the web holder as the needle moves downwardly below the upper edge of the web holder, thereby always insuring a uniform tension on the thread at the loop, and consequently insuring an optimum evenness of the stitch loops and uniformity of knitting action. Due to the curved configuration of the upper edge of the arm 8' on each web holder, as shown in the drawings, the web holders will automatically assume a position imparting a uniform tension to the stitch loops as they are drawn by the needles, regardless of the length of the stitch loop drawn, the web holders automatically rocking inwardly or outwardly to a greater or less extent over and above the rocking movement directly imparted to the web holders by the cams 11 and 12 to compensate for any tendency of reduction or increase of tension. This automatic compensation of tension is permitted by the yieldable mounting of the web holder-cams 11 and 12, which will now be particularly described.

It will be understood that the number of web holder-cams 11 and 12 corresponds to the number of thread feeds, and there is one of each of these web holder-cams 11 and 12 for each needle raise-cam and draw-cam, according to the relation-

ship illustrated in Figure 9. In the case of multiple feed machines, each of the web holder-cams 11 which serves to rock the web holders inwardly is mounted on the upper end of the cam ring 10, being preferably recessed flush with the upper face of the latter. Each cam 11 is fixed to the cam ring by a screw 46 passing vertically downwardly through the cam and having threaded engagement with the cam ring 10. The cam is free to pivot on the screw 46, but is normally yieldably pressed inwardly towards the web holders by means of a spring 47 encircling the screw and interposed between the head of the screw and the upper side of the web holder. One end 15 of the spring 47 is fixed to the screw, as by engaging the upper end of the spring in an opening 48 in a nut 49 disposed on the screw 46 next to the screw head, and the lower end of the spring is offset and hooked over the outer edge of the cam, as indicated at 50 in Figure 5. To vary the yieldable pressure of the spring 47 tending to urge the cam 11 in an inward direction towards the web holders, it is simply necessary to loosen the screw 46 and then turn the nut 49 in one direction or the other to either loosen or tighten the coils of the spring, and then retighten the screw 46 to lock the nut 49 in its adjusted position.

The shape of the cams 11 is best illustrated in Figure 5, wherein it will be seen that each cam is provided with an inclined cam face 51 which serves to bear against the outer edges of the web holders 8 at a point above the fulcrum point of the web holders provided by the bosses 25 seated 20 in the annular groove 23 in the needle cylinder 6. It will also be seen from Figure 5 that each cam 11 is provided with an enlarged aperture 52, through which the adjusting screw 41 for the adjustable needle draw-cams passes. The aperture 52 is sufficiently large to afford clearance for the head of the adjusting screw 41 to allow the adjusting screw to be screwed down below the cam and permit its adjustment without disturbing the cam.

45 The web holder-cams 12 are pivotally mounted in an annular groove 53 formed in the inner face of the cam ring 10, each web holder being secured in the groove 53 by a screw 54 passing downwardly from the upper side of the cam ring 10 through the cam 12 near one end of the latter. The upper end of the screw 54 is preferably recessed in the cam ring below the plane of the cams 11 so that it will not interfere with the movement of the latter, and the lower extremity of the screw 54 is preferably reduced in size and has the form of a smooth pin, as at 55, on which the cam 12 is free to pivot towards and away from the web holders. Each cam 12 is normally yieldably pressed inwardly towards the web holders by 50 means of a spring 56 disposed in a radial bore 57 in the cam ring 10, one end of the spring bearing against the edge of the cam at its free end, and the opposite end of the spring being engaged by an adjusting screw 58 having threaded engagement with the bore 57. Pressure of the spring 56 may be varied by screwing the adjusting screw 58 in one direction or the other, as will be obvious. Each cam 12 is notched at 59 to afford clearance for the needle draw-cam adjusting screw 41 hereinbefore referred to, and the cam is provided with an inclined cam edge 60 which is adapted to successively engage the butts of the web holders below their fulcrum point.

It is important that the pivotal axis of each cam 12, as afforded by the pin 55 on the end of

the screw 54, and the pivotal axis of each cam 11 formed by the screw 46, be properly located with respect to each other and with respect to the needle cams so as to position the working edges 60 and 51 of the respective cams at the proper position to suitably time the rocking or pivotal movements of the successive web holders in the appropriate relation to the needle movement as hereinbefore referred to. This relationship is best understood by comparing Figures 4, 5 and 6 and Figure 9.

Due to the yieldable spring pressure on the web holders-cams 11 and 12, these cams will automatically adjust themselves to allow the web holders to regulate themselves according to the length of the stitch drawn by each needle as hereinbefore referred to. In addition, the automatic adjustment of the web holders and their cams prevents jamming or smashing of the machine in the case of a defective yarn having lumps or knots therein, since the springs acting on the web holders-cams will yield and allow the lumps or knots in the yarn to freely pass over the web holders.

It will be understood from the foregoing that all of the web holder-cams and all of the needle cams are carried by the common cam ring and ring gear so as to be rotatable with the latter about the needle cylinder, and free access may be readily had to the web holders and needles by dismounting one or more segments of the cam ring. To prevent the web holders and needles from becoming inadvertently displaced from the needle cylinder; especially when the cam ring or any part thereof is dismounted, there is preferably provided a coil-spring ring 61 which encircles the needle cylinder exteriorly of the needles and web holders and yieldably engages the latter at a point about opposite to the fulcrum points of the web holders, as will be best understood from reference to Figures 1 to 8, 7 and 10. Due to the yieldable retaining action of this ring 61, any individual web holder or needle, or group thereof, may be removed from the needle cylinder without disturbing the others, and the retaining ring further insures against inadvertent dropping of stitches on the other needles when it becomes necessary or desirable to remove or exchange certain web holders or needles. The marked simplicity of construction of each component part of the machine, and the ease of adjustment thereof to assure the desired stitch loop tension and uniform length of stitch loops, together with the smoothness of operation of the machine and the inherent uniformity of knitting action and high quality fabric produced thereby, will be strikingly apparent from the foregoing description, taken in conjunction with the illustrations in the drawings.

Referring now to Figures 17 and 18, these figures show a modified form of web holder, generally designated 108, which is quite similar to the web holder 18 hereinbefore referred to, excepting that it is provided with a substantially longer nose 144 disposed above the arm 108. This modified web holder 108 is also provided with a lug or boss 125 constituting the fulcrum about which the web holder is free to rock or pivot in exactly the same manner as hereinbefore described. In using the web holders 108, the setup of the knitting machine and its operation is exactly the same as previously described, excepting that at each thread feed two separate threads T' and T'' are fed into the needles 7 by each thread guide, one thread, T', being presented to the needles above the other thread T'' so that

there is sufficient space therebetween to allow the nose 144 of each web holder 108 to lie between the threads, as indicated in full lines in Figure 17, and also in Figure 18. On downward movement of the needles 7, successively as before, each needle pulls the two threads downwardly below the upper ends of the associated web holders 108, forming two stitch loops 'L' and L'' on each needle, the loop L' being longer than the loop L'' by reason of the fact that the thread T' is drawn across the upper edge of the nose 144, as clearly shown in broken lines in Figure 17. Both of the loops L' and L'' will be tensioned in the same manner as already described, and each web holder will automatically maintain the loop tension uniform and will always hold down the fabric snugly onto the upper end of the cylinder by engagement of the nose 144 of the web holders 108 over the edge of the fabric at the top of the cylinder, excepting when the web holders are rocked outwardly to their position shown in broken lines in Figure 17, which occurs in timed relation to the needle movement as before. In forming the double stitches on each needle in the manner just described with one stitch loop longer than the other, the resulting fabric will be comprised of a body of plain stitches similar to those formed in the manner shown in Figure 1, with the surface of the fabric presenting long loops which characterizes a loop fabric. By suitably pattern-controlling the web holders 108 to withdraw the nose 144 of each web holder from between the threads T' and T'', the loop-surface of the fabric can be confined to predetermined areas forming various designs. Otherwise, the loop-surface will be uniform over the entire face of the knitted fabric.

It will be understood by those skilled in the art that the machine hereinbefore described is intended essentially to knit plain stitches or loops, but there is no intention of limiting the invention thereto where suitable provision may be made to produce stitches of other types. It will be obvious that by feeding threads of contrasting colors to the needles at varicous feeds about the needle circle, striped fabrics can be readily produced, with the stripes alternating in conformance with the order of the colored threads presented to the needles at the different feeds.

While the specific details have been herein shown and described, the invention is not confined thereto, as changes and alterations may be made without departing from the spirit thereof as defined by the appended claims.

Having thus described my invention, what I claim as new and desire to secure by Letters Patent is:

1. A knitting machine of the class described, comprising a support, a plurality of needles mounted on said support for endwise movement in upward and downward directions, a plurality of web holders pivotally mounted on said support with one web holder between each pair of adjacent needles, and the direction of pivotal movement of the web holders being crosswise to the direction of movement of the needles, means for feeding a thread to successive needles at a point above the web holders, means for successively imparting endwise movement to the needles to draw the thread across and below the end of an adjacent web holder and through a previously formed loop on its contiguous needle to form another stitch loop and maintain the same under tension by the web holder, means on the web holders for normally engaging the edge of the

knitted fabric when the web holders are in one position of their pivotal movement to hold the fabric down on the support as it is knitted, and yieldable means for imparting pivotal movement to the web holders in timed relation to the needles, said last-named means serving to successively move the web holders to a position releasing their holding down engagement with the fabric as the needles draw the thread across and below the ends of the web holders in the formation of the stitch loops, said yieldable means serving to automatically and uniformly tension the thread irrespective of the lengths of stitch loops drawn by the needles.

2. A knitting machine of the class described, comprising an axially erect cylinder having in its outer face a plurality of circumferentially spaced slots axially extended from the upper end of the cylinder to approximately midway of the length of the cylinder, and having a circumferential groove intersecting said slots near their lower ends, the upper edge of the cylinder being correspondingly slotted radially in register with the upper ends of the axially extended slots, a web holder incuted in each slot and each web holder having a body portion disposed in one of the axially extended slots and having a projection on the body thereof disposed in the circumferential groove and constituting a fulcrum on which the web holder is adapted to rock to afford movement of the upper end of the web holder towards and away from the axis of the cylinder, and each web holder further having an arm at its upper end extending radially inwardly therefrom and lying in a corresponding radial groove in the upper end of the cylinder, a needle mounted on the cylinder between each pair of adjacent web holders and movable vertically therebetween in an upward and downward direction, means for successively raising the needles to receive a thread above the web holders, means for successively drawing the needles downwardly to successively draw a loop across and below the upper edge of the arm of the web holder adjacent to the downwardly moving needle, means on the upper end of each web holder normally engaging the edge of the knitted fabric formed by the loops aforesaid to hold the fabric down on the upper end of the cylinder when the upper end of the web holder is rocked inwardly on its fulcrum, and means yieldably acting upon the web holders at opposite sides of their respective fulcrums for successively imparting rocking movement to said web holders, said last named means being so timed with relation to the needles that the web holders are rocked outwardly to release their holding down engagement with the fabric as the upper ends of the needles approach the upper ends of their adjacent web holders in their downward loop-drawing movement, and the web holders are rocked inwardly prior to commencement of the raising movement of the needles.

3. Apparatus as defined in claim 2, wherein the needles are mounted on the outer face of the cylinder between circumferentially spaced axially extended guide plates disposed on the cylinder below the web holders.

4. Apparatus as defined in claim 2, wherein the needles are mounted on the outer face of the cylinder between circumferentially spaced axially extended guide plates disposed on the cylinder below the web holders, the face of the cylinder being slotted in substantial alignment with the

web holder slots to receive the guide plates, and each adjacent pair of guide plates defining a needle guideway therebetween lying in a radial plane intermediate the web holders.

5. A knitting machine of the class described, comprising a cylinder, a circle of needles mounted on the cylinder in circumferentially spaced relation to each other and movable endwise in the performance of a knitting action, a plurality of web holders also mounted on the cylinder for rocking movement in a plane transverse to the endwise movement of the needles with a web holder interposed between each pair of adjacent needles, means for feeding a thread into the needles at a point above the web holders, means for alternately moving the needles endwise in opposite directions and in successive order about the needle circle to alternately engage the thread and draw stitch loops, means on said web holders for engaging the thread as the stitch loops are successively drawn by the needles, said web holders also having means intermittently engageable with the edge of the fabric formed by the stitch loops to hold down the fabric snugly on the cylinder as the same is knitted, and means for imparting an automatically yieldable rocking movement to the web holders successively about the needle circle in timed relation to the loop drawing and thread engaging movements of the needles, said last named means constituting means for maintaining a uniform tension on the thread when engaged by the web holders, and for automatically regulating the position of the web holders according to the length of stitch loops drawn by the respective needles.

6. A knitting machine of the class described, comprising a support, a plurality of needles mounted on said support for endwise movement in opposite directions, a plurality of web holders pivotally mounted on said support with one web holder between each pair of adjacent needles, and the direction of pivotal movement of the web holders being crosswise to the direction of movement of the needles, means for feeding a thread to successive needles at a point above the web holders, means for successively imparting endwise movement to the needles to draw the thread across and below the end of an adjacent web holder and through a previously formed loop on its contiguous needle to form another stitch loop and maintain the same under tension by the web holder, means on the web holders for normally engaging the edge of the knitted fabric when the web holders are in one position of their pivotal movement to hold the fabric down on the support as it is knitted, and spring-pressed cam means for imparting pivotal movement to the web holders in timed relation to the needles, and serving to successively move the web holders to a position releasing their holding down engagement with the fabric as the needles draw the thread across and below the ends of the web holders in the formation of the stitch loops, said cam means including a pair of cam members disposed for engagement with the web holders and located at points on opposite sides of the pivotal axis of the web holders, and said cam members being mounted for yieldable pivotal movement about an axis generally normal to the pivotal axis of the web holders, and means for adjusting the spring pressure upon said cam members.

CERTIFICATE OF CORRECTION.

Patent No. 2,329,617.

September 14, 1943.

WILLIS A. INGALLS.

It is hereby certified that error appears in the above numbered patent requiring correction as follows: In the drawings, Sheet 3, at the top of Figures 9 and 15 respectively, for the legends "WEB HOLDERS", "WEB HOLDERS" and "WEB HOLDERS" read --WEB HOLDERS IN--, --WEB HOLDERS OUT-- and --WEB HOLDERS IN--; and that the said Letters Patent should be read with this correction therein that the same may conform to the record of the case in the Patent Office.

Signed and sealed this 2nd day of November, A. D. 1943.
